US00D486909S

(12) **United States Design Patent** (10) Patent No.: **US D486,909 S**
 Cise et al. (45) Date of Patent: ** *Feb. 17, 2004

(54) **BENDABLE CONNECTING DEVICE**

(75) Inventors: **David M. Cise**, Herriman, UT (US); **Edward B. Madsen**, Riverton, UT (US); **L. John Teuscher**, Springville, UT (US)

(73) Assignee: **Kimberly-Clark Worldwide, Inc.**, Neenah, WI (US)

(*) Notice: This patent is subject to a terminal disclaimer.

(**) Term: **14 Years**

(21) Appl. No.: **29/147,351**

(22) Filed: **Aug. 27, 2001**

(51) LOC (7) Cl. **23-01**

(52) U.S. Cl. **D24/129; D24/110**

(57) **CLAIM**

We claim the ornamental design for a bendable connecting device, as shown and described herein.

DESCRIPTION

FIG. 1 is a perspective view of the bendable connecting device of the present invention.

FIG. 2 is another perspective view of the bendable connecting device of the present invention.

FIG. 3 is an end view of the bendable connecting device depicted in FIG. 4.

FIG. 4 is a side view of the bendable connecting device of the present invention; and,

FIG. 5 is another end view of the bendable connecting device depicted in FIG. 4.
